LATCH MECHANISM FOR DISAPPEARING
WARDROBE DOORS

Joseph F. Schaefer, Bay Village, Ohio, assignor
to The Interior Steel Equipment Company,
Cleveland, Ohio, a corporation of Ohio

Application March 25, 1950, Serial No. 151,835

3 Claims. (Cl. 70—264)

1

This invention relates to door latch mechanism and, more particularly, to an improved latch mechanism for controlling the movement of a group of swinging doors. This improved latch mechanism can be used to advantage with various kinds of swinging doors but is especially applicable to so-called disappearing doors of the kind used for built-in school wardrobes and is disclosed herein as applied to that use but without any intention of limiting the invention in this respect.

An object of the present invention is to provide an improved latch mechanism for swinging doors in which holding members adapted for co-operation with the doors are carried by a rock-shaft and are movable to and from an effective door-holding position by rocking movement imparted to such shaft.

Another object is to provide an improved latch mechanism for grouped self-closing doors in which holding members carried by a rockshaft are adapted to be moved, by rocking of the shaft in one direction, to a position effective for holding the doors in their open position and in which rocking of the shaft in the opposite direction causes the holding members to release all of the open doors for self-closing movement.

As a further object, this invention provides improved latch mechanism of the character mentioned in which the doors carry latch devices adapted for releasable engagement with the holding members to permit the doors to be manually moved to and from the open position while the holding members are in their effective position.

Still another object is to provide improved latch mechanism for a group of swinging doors in which locking members carried by a rockshaft are adapted to be moved, by rocking of the shaft in one direction, to a position effective for holding the doors in their closed position and in which rocking of the shaft in the opposite direction causes the locking members to release the doors for opening movement.

A further object is to provide latch mechanism of this character in which the doors carry latch devices adapted for cooperation with the locking members by having spring-pressed plungers which are movable past the locking members during movement of the doors to their closed position and in which abutment elements on such locking members and plungers cooperate to prevent opening of the doors while the locking members are in their effective position.

It is also an object of this invention to provide key-operated means for controlling the actuation of the rockshaft.

2

Yet another object is to provide improved latch mechanism for a group of substantially aligned doors mounted for manual opening and self-closing swinging movements, in which holding members and locking members adapted for co-operation with the doors for holding them in open and closed positions, respectively, are carried by a common rockshaft and are movable thereby into and out of effective positions and in which latch devices carried by the doors cooperate with the holding members so as to be movable past the same in either direction and cooperate with the locking members so as to be movable past the same only during closing movement of the doors.

15 This invention can be further briefly summarized as consisting in certain novel combinations and arrangements of parts hereinafter described and particularly set out in the claims hereof.

20 In the accompanying sheets of drawings, Fig. 1 is a front elevation showing a school wardrobe having a group of swinging doors equipped with the latch mechanism of this invention;

25 Fig. 2 is a transverse section taken through the wardrobe at a point above the tops of the doors and above the latch mechanism, as indicated by section line 2—2 of Fig. 1;

30 Fig. 3 is a transverse section taken through one pair of doors and on a somewhat larger scale, the view being taken as indicated by section line 3—3 of Fig. 1;

35 Fig. 4 is an elevation further illustrating the doors and latch mechanism, with the doors in their closed position and with the latch mechanism in its locking position, the view being taken from a point inside the wardrobe and looking toward the doors substantially as indicated by section line 4—4 of Fig. 2;

40 Fig. 5 is a partial vertical section taken through the wardrobe at a point between one pair of closed doors, substantially as indicated by section line 5—5 of Fig. 4;

45 Fig. 6 is a partial vertical section similar to Fig. 5 but with the nearest door open and with the latch mechanism in position for holding this door open;

50 Fig. 7 is a partial vertical section further illustrating the construction and operation of the latch mechanism, the view being taken on section line 7—7 of Fig. 6 and showing one door in open position and an adjacent door in closed position;

55 Fig. 8 is a partial transverse section taken on section line 8—8 of Fig. 5 and showing key-operated means for controlling the latch mechanism; and

Fig. 9 is a fragmentary detail providing a larger scale showing of one of the holding members and latch device cooperating therewith.

In proceeding with the detailed description, reference will be made first to the general views of Figs. 1 and 2 in which the improved latch mechanism 10 forms a part of a built-in wardrobe 11 of the kind frequently used in school buildings. The wardrobe 11 is here shown as including a compartment 12 recessed into a wall 13 and having a front opening which is closed by a group or battery of doors 14 which, in their closed position, are in a substantially co-planar relation in alignment with the wall 13. As here shown, the doors 14 are preferably arranged in pairs comprising right- and left-hand doors 14a and 14b, and are mounted for swinging movement so as to recede or disappear into the compartment 12 when the doors are swung to their open position.

The front opening of the compartment 12 is divided into a number of doorways 15 by spaced upright door posts 16 and each such doorway is controlled by a pair of the swinging doors 14. As shown in Figs. 3 and 8, the door posts 16 can be formed by a pair of upright channel members 16a and 16b disposed in back-to-back relation. At their lower ends the door posts 16 are supported on the floor 17 and at their upper ends are connected with a longitudinally extending frame or lintel 18. The lintel 18 can be of any suitable construction, such as that herein illustrated, in which this member is formed by a bar 18a of a substantially right-angle cross-sectional shape which is attached to the arch 19 of the building wall 13 and a substantially Z-shaped bar 18b which is attached to the depending flange of the bar 18a as by means of the screws 20. The longitudinal space between the bars 18a and 18b can be closed by a longitudinally extending sheet metal trim member 21.

The pairs of swinging doors 14a and 14b are mounted on the door posts 16 for inward swinging movement by means of a pair of suitable upper and lower hinges 22 and 23 for each door. In this instance, the hinges 22 and 23 are shown as being of the type comprising an angular bracket 24 which is attached to the door post 16 and carries a large pin 25, and a sleeve or bushing 26 connected with the door 14 and pivoted on the hinge pin 25. In the construction here shown the brackets 24 are mounted on the door post 16 so that the hinge pins 25 thereof extend toward each other in a substantially vertically aligned relation and the sleeves 26 are mounted in the hollow edge portion or hinge stile 26a of the door so that the hinge pins extend thereinto through the top and bottom edges of the door. The vertical spacing between the brackets 24 of the upper and lower hinges 22 and 23 is greater than the height of the door 14 as to leave an intervening space 27 at the upper hinge 22 which will accommodate an upward shifting movement of the door, for a purpose to be explained herein-after.

The doors 14 are preferably self-closing doors which will normally swing to their closed position in the above-mentioned co-planar relation. Such a self-closing movement for the doors can be provided by the use of door hinges having a suitable self-closing spring means embodied therein or preferably, as shown in this instance, by providing a gravity actuated self-closing means. The gravity actuated self-closing means here shown comprises an inclined track member 28 mounted on the lower hinge bracket

24 and an anti-friction roller 29 mounted on the door and adapted to ride on this track member.

During opening of the doors by a manual inward swinging thereof the rollers 29 travel up the inclined track members 28, thereby lifting the doors a corresponding distance which is permitted by the above-mentioned intervening space 27. When the doors which have been thus opened are released, they will swing back automatically to their closed position and will come to rest in the above-mentioned co-planar relation. The closing force for the doors is provided by the weight of the doors acting through the rollers 29 on the inclined track members 28 as the result of which the rollers tend to travel down the track members, thereby swinging the doors toward the closed position.

The improved latch mechanism 10 provided by this invention includes a rockshaft 30 which extends longitudinally of the wardrobe compartment 12 at a point above the tops of the doors 14. The shaft 30 is rockably mounted in suitable supports which are here shown in the form of supporting arms 31 extending rearwardly from the longitudinal Z-bar 18b of the lintel structure 18. The latch mechanism 10 also includes holding members 32 carried by the rockshaft 30 and which are movable by the latter to an effective position in which they will be engaged by latch devices 33 carried by the doors 14 for holding the doors in their open position.

The holding members 32 are here shown as being located on the underside of the rockshaft 30 and as being formed by the heads of screws 34 which extend through openings of this shaft. The heads of the screws 34 are of such shape that the holding members 32 will have a downwardly converging taper or bevel 35 on opposite sides thereof which will permit the latch device 33 of the door 14 to move past such holding member for either direction of swinging travel of the door. This downwardly converging taper on the holding members 32 can be readily obtained by making the screw heads of the conical shape here shown.

As shown in the drawings, the latch devices 33 of the doors 14 are of the type comprising a casing 36 mounted on the door and a plunger 37 adapted to be extended from such casing by a compression spring 38 located therein. The end of the plunger 37 cooperates with the holding member 32 and, for this purpose, is provided with upwardly converging flat beveled faces 39 on opposite sides thereof so that this plunger can be made to ride over and travel past the holding member 32 for either direction of swinging movement of the door.

Thus when one of the doors 14 is manually swung to its open position the plunger 37 will engage the holding member 32 and, by reason of the beveled faces provided on the holding member and plunger, the latter will be able to ride over the holding member and assume a position in back of the holding member, as shown in Fig. 7. When the plunger 37 is in this position it will cooperate with the holding member 32 for retaining the door 14 in its open position, but such holding engagement of the plunger 37 with the member 32 will be a releasable engagement such that the door can be readily closed by a manual closing effort applied thereto. When such manual closing effort is applied to the door 14 the plunger 37 of the latch device 33 will again travel over the holding member 32 after which the door is free to swing

to its closed position under the influence of the self-closing action explained above.

When some or all of the doors 14 are standing in their open position they can be released simultaneously for self-closing movement by rocking the shaft 30 to cause the holding members 32 to be disengaged from the plunger 44 of the latch devices 33. The rocking movement thus imparted to the shaft 30 is a clockwise movement, as seen in Figs. 5 and 6, and shifts the holding members 32 from their effective position shown in Fig. 6 to their ineffective position shown in Fig. 5. Rocking of the shaft 30 in the opposite direction shifts the holding members to their effective position (shown in Fig. 6) which is their normal position because they are then ready to be engaged by the plungers 37 whenever the doors 14 are swung to their open position.

The swinging of the rockshaft 30 to shift the holding members 32 out of their effective position can be accomplished by any suitable mechanism, such as the linkage shown in this instance, and which includes a rearwardly projecting lever 40 connected with the rockshaft and a link 41 having its upper end pivotally connected with this lever. The lower end of the lever 41 is pivotally connected with the arm 42a of a bellcrank lever 42, which is pivoted on the door post 16 for swinging movement by means of the screw 43. This actuating mechanism for the rockshaft 30 also includes a plunger 44 which is slidably mounted in an opening of the door post 16 and is operatively connected with arm 42b of the bellcrank lever 42.

The operating connection between the plunger 44 and the arm 42b of the bellcrank lever 42 can be formed by a slot 45 provided in this arm and a pin 46 carried by the plunger and engaging in this slot. The plunger 44 is provided at the forward end thereof with a knob or handle 47 which is adapted to be manually grasped for imparting an inward and outward movement to this plunger. An outward movement imparted to the plunger 44 causes swinging of the bellcrank lever 42 in a clockwise direction, thereby transmitting an upward thrust to the lever 40 through the link 41 which rocks the rockshaft 30 in a clockwise direction to move the holding members 32 to their ineffective position shown in Fig. 5. Inward movement of the plunger 44 causes a counter-clockwise swinging of the bellcrank 42, thereby transmitting a downward pull to the lever 40 through the link 41 and thus swinging the rockshaft in a counter-clockwise direction to move the holding members 32 to their effective position shown in Fig. 6, in which they will be engaged by the plungers 37 of the latch devices 33 when the doors are manually swung to their open position.

As indicated above, the normal position for the rockshaft 30 is that shown in Fig. 6 in which the holding members 32 are in their effective position ready to be engaged by the latch devices 33 of the doors 14. The rockshaft 30 can be made to automatically assume this position as by providing a counterweight 48 on the lever 40, or by providing some other equivalent means such as a suitably arranged tension spring. From the arrangement described it will be seen that unless the rockshaft 30 is prevented from doing so, it will, under the influence of the counterweight 48, automatically assume its normal position. Whenever it is desirable to maintain the holding members 32 in their ineffective position shown in Fig. 5, this can be done by

a key-actuated locking device 50 provided on the door post 16 on which the plunger 44 is mounted and which locking device cooperates with the bellcrank lever 42.

The locking device 50 is here shown as having a bolt member 51 which is adapted to be swung by means of a key 52 and which is movable into a holding position with respect to a finger 53 carried by the arm 42b of the bellcrank lever 42. When the holding members 32 are in their ineffective position, as shown in Fig. 5, the finger 53 of the bellcrank lever 42 will occupy an upright position alongside of the post 16, at which time the bolt member 51 can be moved into a holding position in back of this finger by rotation of the key 52. When the holding members 32 are to be returned to their effective position, the key 52 is rotated in the opposite direction to swing the bolt member 51 to a retracted position, thereby releasing the finger 53 and permitting the link 41 to drop down to the position shown in Fig. 6 under the influence of the counterweight 48, thereby rocking the shaft 30 and moving the holding members 32 to their effective position. As shown in Figs. 5 and 6, the plunger 44 is preferably provided with inner and outer bumpers 54 and 55 formed of yieldable cushioning material, such as sponge rubber, and which are engageable, respectively, with opposite sides of the door post 16 during outward and inward movements of this plunger.

When some or all of the doors 14 are standing in the open position they can be individually disengaged from the holding members 32 by a manual force applied to the doors, as explained above, or all of the open doors can be simultaneously released for self-closing swinging movement by rocking the shaft 30 to the position of Fig. 5 by withdrawing the plunger 44. Immediately upon the withdrawal of the plunger 44, the open doors will begin to swing toward their closed position and the initial portion of this swinging movement will cause the latch devices 33 to move clear of the holding members 32. As soon as the plunger 44 has been withdrawn to initiate such closing movement of the open doors, the plunger can be immediately released, which will permit the counterweight 48 to rock the shaft 30 in the opposite direction to return the holding members 32 to their effective position. The latch mechanism 10 can be left in this condition and whenever one or more doors are left standing open they can be released for automatic closing merely by pulling out the plunger 44.

Another important feature of this invention is the provision of locking members 58 for holding the doors 14 in their closed position. These locking members are mounted on the rockshaft 30 so as to lie opposite the meeting points of the pair doors 14a and 14b when such paired doors are in their closed position. The locking members 58 are here shown as being arms which are suitably mounted on the rockshaft 30 so as to extend therefrom in a generally forward direction. One such locking member is provided on the rockshaft 30 for each pair of doors and when these members are in their effective position for preventing opening of the doors, they extend forwardly and downwardly toward the doors as shown in Fig. 5.

For cooperation with the locking members 58, the doors 14 are provided with latch devices 59 which are generally similar to the latch devices 33 described above. The latch devices 59

are mounted on the upper ends of the doors 14 adjacent their meeting edges and each of these latch devices comprises a casing 60 attached to the door and a plunger 61 normally held in a partially projected position by a compression spring 62 contained in the casing. The latch devices 59 differ from the latch devices 33 in that the plunger 61 has a bevel 63 on only one side thereof and on the opposite side is provided with a straight or flat abutment face 64. The end of the locking member 58 is provided with a recess 65 adapted to receive the plunger 61 and is also provided with an abutment element 66 which cooperates with the abutment face 64, as shown in Fig. 5, for preventing opening movement of the door.

When the locking members 58 are in their effective position, the doors 14 can swing to their closed position because the bevel faces 63 of the latch devices 59 will permit the plungers 64 thereof to readily move past the abutment elements 66 of the locking members. As soon as the doors reach their closed position the plungers 64 will engage in the recesses 65, whereupon the abutment elements 66 will be engaged by the flat abutment faces 64 of the plungers to prevent opening movement of the doors. The doors will be maintained in their locked position as long as the locking members 58 occupy their effective position shown in Fig. 5 and this condition can be maintained during classroom periods or at other times when pupils are to be excluded from the wardrobe compartment 12.

When the doors of the wardrobe 11 are to be unlocked to permit access to the compartment 12, it is only necessary to swing the bolt member 51 by rotation of a key 52 in the locking device 50 to thereby release the finger 53 of the bellcrank lever 42, whereupon the counterweight 48 will move the rockshaft 30 to shift the locking members 58 from their effective position to their ineffective position. This same actuation of the shaft 30 will shift the holding members 32 to their effective position as previously explained herein.

Although the latch mechanism 10 is illustrated herein as including the locking members 58 as one feature thereof for maintaining the doors 14 in a locked condition, it should be understood that, if desired, these locking members and the corresponding latch devices 59 can be omitted. When the locking members 58 are thus omitted, the latch mechanism is used for controlling only the open position of the doors.

From the accompanying drawings and the foregoing description it will now be readily understood that this invention provides improved latch mechanism for a battery of swinging wardrobe doors by which individual doors can be releasably retained in an open position, and by which all of the open doors can be simultaneously released for swinging to the closed position. It will also be seen that this invention provides a locking means by which the doors can be locked while in their closed position. Additionally, it will be seen that this invention provides a common rockshaft for simultaneous actuation of all of the door holding and door locking members so that the respective door releasing and door locking functions can be accomplished simultaneously for all of the doors of the group.

Although the improved latch mechanism provided by this invention has been illustrated and described herein to a somewhat detailed extent,

it will be understood, of course, that the invention is not to be regarded as being limited correspondingly in scope but includes all changes and modifications coming within the terms of the claims hereof.

Having thus described my invention, I claim:

1. Latch mechanism adapted to be applied to a door frame and a row of paired doors mounted for swinging movement of the adjacent free edges of each pair of doors to open and closed positions, comprising a holding member for each door of said row, a locking member for each pair of said doors, a rockshaft for mounting on said door frame inwardly of said row of doors and forming a common actuator for said holding members and said locking members, said holding members being movable to an effective position for engaging and holding said doors in the open position by rocking of said shaft in one direction and said locking members being movable to an effective position for engaging and locking said doors in the closed position by rocking of said shaft in the opposite direction, and means for imparting rocking movement to said shaft for moving said holding and locking members into and out of their effective positions.

2. Latch mechanism adapted to be applied to a door frame and a row of paired doors mounted for swinging movement of the adjacent free edges of each pair of doors to open and closed positions, comprising a holding member for each door of said row, a locking member for each pair of said doors, a rockshaft for mounting on said door frame inwardly of said row of doors and forming a common actuator for said holding members and said locking members, said holding members being movable to an effective position for engaging and holding said doors in the open position by rocking of said shaft in one direction and said locking members being movable to an effective position for engaging and locking said doors in the closed position by rocking of said shaft in the opposite direction, means for imparting rocking movement to said shaft for moving said holding and locking members into and out of their effective positions, first latch devices carried by said doors for cooperation with said holding members for releasably retaining the doors in said open position and having spring projected latch elements engageable with said holding members and movable past the same in response to manually imparted swinging movement of the doors in either an opening or closing direction, each of said locking members having an abutment means of a width to span the meeting line between the adjacent free edges of one of said pairs of doors, and second latch devices mounted on said doors adjacent the free edges thereof and having spring projected latch elements engageable with said abutment means for holding the doors in their closed position and being movable past said abutment means during swinging movement of the doors toward their closed position.

3. Latch mechanism adapted to be applied to a door frame and a row of paired doors mounted for swinging movement of the adjacent free edges of each pair of doors to open and closed positions, comprising a holding member for each door of said row, a locking member for each pair of said doors, a rockshaft for mounting on said door frame inwardly of said row of doors and forming a common actuator for said holding members and said locking members, said holding members being movable to an effective position for holding said doors in the open position by rocking of said

shaft in one direction to a normal position and said locking members being movable to an effective position for locking said doors in the closed position by rocking of said shaft in the opposite direction to a locking position, first latch devices carried by said doors for cooperation with said holding members when the latter are in their effective position, said first latch devices having projecting spring-pressed plungers which are movable past said holding members during manual movement of said doors to and from said open position, second latch devices carried by said doors for cooperation with said locking members when the latter are in their effective position, said second latch devices having projecting spring-pressed plungers which are movable past said locking members during closing movement of said doors, abutment elements on said locking members and the plungers of said second latch devices for cooperation in preventing movement

15 20

of said doors out of said closed position, means for imparting rocking movement to said shaft for moving said holding and locking members into and out of their effective positions and tending to rock said shaft to said normal position to locate said holding members in their effective position and said locking members out of their effective position, and key-operated means controlling the last mentioned means and effective to cause said rockshaft to be maintained in said locking position.

JOSEPH F. SCHAEFER.
